UNITED STATES PATENT OFFICE.

JOHN JEPSEN AND JOHN R. CONNOLLY, OF MARICOPA, CALIFORNIA.

MAGNETO-CONTACT.

1,370,114.

Specification of Letters Patent.

Patented Mar. 1, 1921.

Application filed March 20, 1918. Serial No. 223,664.

To all whom it may concern:

Be it known that we, JOHN JEPSEN and JOHN R. CONNOLLY, citizens of the United States, residing at Maricopa, in the county 5 of Kern and State of California, have invented certain new and useful Improvements in Magneto-Contacts, of which the following is a specification, reference being had to the accompanying drawings.

10 This invention relates to certain improvements in magneto contacts and has relation more particularly to a device of this general character especially designed and adapted for use in connection with a magneto embodied in the type of internal combustion engine used in connection with the well known Ford automobile, and it is an object of the invention to provide a device of this general character having novel and improved 15 means whereby the magneto contact and its coacting spring are effectively protected against being broken by brake lining waste and whereby no foreign substance that may be in the oil in use in the motor 20 may interfere with the contact.

25 The invention consists in the details of construction and in the combination and arrangement of the several parts of our improved magneto contact whereby certain important 30 advantages are attained and the device rendered simpler, less expensive and otherwise more convenient and advantageous for use, as will be hereinafter more fully set forth.

35 The novel features of our invention will hereinafter be definitely claimed.

40 In order that our invention may be the better understood, we will now proceed to describe the same with reference to the accompanying drawings, wherein is disclosed a vertical sectional view taken through a magneto contact constructed in accordance with an embodiment of our invention and in applied position, the coacting portion of 45 the crank case being also shown in section.

45 As disclosed in the accompanying drawings C denotes the upper portion of a crank casing as embodied in the well known type of motor employed in connection with the 50 Ford automobile and which is provided with an opening 1. Fitting within the opening 1 is a bushing 2 of non-conductive material which has its outer end provided with the annular flange 3 whereby the same may 55 be suitably anchored or connected to the cas-

ing C. The bore of the bushing 2 is threaded and with which is engaged the member 4 of conductive material. The inner end of the member 4 is provided with an axial bore 5, the inner end portion *a* of said bore being 60 of reduced diameter providing a shoulder. The outer end of the member 4 is adapted to have connected therewith a conductor (not shown) leading to the magneto terminal of a coil box.

65 Seated within the reduced portion *a* of the bore of the member 4 is an end portion of the helical spring 6 of desired length and which has engaged with the outer end thereof, the magneto contact 7.

70 Surrounding the magneto contact 7 and the coacting end portion of the spring 6 is a sleeve 8 of non-conductive material and which sleeve is slidably disposed within the enlarged portion B of the bore of the member 4. Said sleeve 8 is constantly urged outwardly by the helical spring 9 surrounding the first named spring 6 and interposed between the inner end of the sleeve 8 and the shoulder 10 defining the outer end of 75 the reduced portion *a* of the bore of the member 4.

80 As is believed to be obvious from the foregoing description the sleeve 8 effectively protects the magneto contact 7 and the coacting portion of the spring 6 against being broken by brake lining waste and any foreign substance that may be in the oil used in the motor cannot foul the same.

85 From the foregoing description, it is 90 thought to be obvious that a magneto contact constructed in accordance with our invention is particularly well adapted for use by reason of the convenience and facility with which it may be assembled and operated and it will also be obvious that our invention is susceptible of some change and modification without departing from the principles and spirit thereof and for this reason we do not wish to be limiting ourselves to the precise arrangement and formation of the several parts herein shown in carrying out our invention in practice except as hereinafter claimed.

95 100 105
We claim:

A magneto contact comprising a member having an axial bore closed at one end, a portion of the bore being reduced in diameter forming a shoulder, a helical spring having one end seated in the reduced por- 110

tion of the bore and the other end projecting beyond the open end of said bore, a contact in electrical and mechanical connection with the projecting end of the spring, a sleeve of insulating material telescopically engaged within the larger portion of the bore and housing the contact, and a second helical spring having one end seating against said shoulder surrounding the first 10 named spring and bearing at its other end

against the sleeve to urge the latter outwardly.

In testimony whereof we hereunto affix our signatures in the presence of two witnesses.

JOHN JEPSEN.

JOHN R. CONNOLLY.

Witnesses:

H. H. BELL,

J. D. HALL.
